UNITED STATES PATENT OFFICE

172,647

FOLDING DOOR

Charles W. Reene, Janesville, Wis., assignor to
The Hough Shade Corporation, Janesville, Wis.,
a corporation of Connecticut

Application December 4, 1953, Serial No. 27,931

Term of patent 14 years

(Cl. D13—1)

To all whom it may concern:

Be it known that I, Charles W. Reene, a citizen of the United States and a resident of Janesville, in the county of Rock and State of Wisconsin, have invented a new, original, and ornamental Design for a Folding Door, of which the following is a specification, reference being had to the accompanying drawings, forming part thereof.

Fig. 1 is a front view;

Fig. 2 is an enlarged fragmentary section and;

Fig. 3 is a perspective view of a folding door showing my new design.

The broken lines shown in Fig. 1 are for illustrative purposes only.

The characteristic feature of my design consists in the use of a plurality of relatively narrow contiguous slats separated by one or more relatively wide slats.

I claim:

The ornamental design for a folding door, substantially as shown and described.
